DESIGN FOR A WRENCH OR SIMILAR ARTICLE

Clarence Milborn Mayo, Oklahoma City, Okla.

Application April 20, 1943, Serial No. 110,006

Term of patent 14 years

To all whom it may concern:

Be it known that I, Clarence Milborn Mayo, a citizen of the United States, residing at Oklahoma City, in the county of Oklahoma and State of Oklahoma, have invented a new, original, and ornamental design for a Wrench or Similar Article, of which the following is a specification; reference being had to the accompanying drawing, forming a part thereof.

Figure 1 is a top plan view of a wrench showing my new design.

Figure 2 is an edge view thereof.

I claim:

The ornamental design for a wrench or similar article, as shown.

CLARENCE MILBORN MAYO.
